Fig. 5.

UNITED STATES PATENT OFFICE.

EPHRAIM J. KEITH, OF SIKESTON, MISSOURI.

DITCH-DIGGING MACHINE.

1,315,512.

Specification of Letters Patent.

Patented Sept. 9, 1919.

Application filed February 8, 1919. Serial No. 275,734.

To all whom it may concern:

Be it known that I, EPHRAIM J. KEITH, a citizen of the United States, residing at Sikeston, Scott county, and State of Missouri, have invented a new and useful Ditch-Digging Machine, of which the following is a specification.

This invention relates to ditch digging machines.

10 An object of the invention is to provide an improved machine adapted for use in making excavations, digging trenches, ditches and the like, equipped with mechanism for effecting perfect control of the 15 operation of the dipper in excavating, and in discharging the excavated material from the dipper.

Another object is to make various improvements of a general and specific nature 20 in the construction and mode of operation of the machine, all of which objects will appear from the following description in which reference is made to the drawing illustrating an embodiment of the invention, and 25 in which—

Figure 1 is a view showing the machine in operation with the dipper taking on a load.

Fig. 2 is a view showing the operation of the machine in discharging the material 30 from the dipper.

Fig. 3 is a view showing the connection of the dipper handle or arm with the boom.

Fig. 4 is a view showing the construction by which the boom arm is supported in connection with the upright or mast.

Fig. 5 is a plan view showing the construction of the boom, the mast being shown in section.

Fig. 6 is a detailed view showing a portion 40 of the mast in section and illustrating the spaced holes through the mast for receiving the bolts of the boom supporting bracket.

Fig. 7 is a view showing a portion of the dipper handle in section and illustrating the 45 spaced holes through the dipper handle for receiving the bolts of the handle supporting bracket.

As shown the upright or mast 1 is equipped with spherical journal members 2 on its upper and lower ends. The journal member 2 at the lower ends of the mast is fitted within a recess in a support 3. The support 3 is rigidly secured upon the lower frame 4 of the machine. The journal member 2 at the upper end of the mast is similarly fitted within a bearing member 5 se-

cured to the rigid part 6 of the frame. The frame includes the obliquely disposed members 7 having their lower ends secured to the base or lower frame 4 and having connection 60 with the part 6 whereby the latter is rigidly sustained. Additional frame members 8 may be employed if desired with their upper ends bracing and strengthening the member 7.

65 The mast mounted in the manner described is revoluble around a vertical axis in order to swing the dipper laterally to different positions. The mast 1 may be rocked or revolved around its vertical axis by any appropriate device such, for instance, as a large wheel 9 secured to the mast and having a rope or cable 10 passing around the same one or more times and arranged to be operated by an engine or motor, not shown, in 70 a usual and well known manner.

75 The boom is composed of two arms or beams 11 arranged parallel with each other and held in spaced relation by interposed blocks 12. The inner ends of the beams 11 embrace the mast 1 between them and are supported by a pivot 13 passing through the ends of the beams 11 and through a bracket 14 bolted to the inner side of the mast 1. It will be observed that by this construction the 80 boom, which is composed of the beams 11, is pivotally supported at the inner side of the mast and is held from turning or twisting by the contact of the beams 11 with the sides of the mast. In practice this has been found 85 to be a very strong and efficient construction which is much superior to any construction with which I am familiar, both because of the strength and durability of the mounting, as well as because of the equalizing or balancing of the weights and forces upon the 90 mast.

95 The boom 11 may be supported in different adjusted positions upon the mast. The adjustment of the boom in different positions 100 is made possible in the particular embodiment shown by providing means for securing the bracket 14 in selected positions on the mast. For this purpose spaced holes 13^a are formed through the mast adapted to receive the bolts which support the bracket, so that the bracket may be bolted to the mast 105 at any desired altitude.

110 The boom supports a sheave 15 between the beams 11 approximately midway between the mast 1 and the outer ends of the beams. The position of the pulley 15 may

be varied, for instance, said pulley may be moved toward and away from the mast as desired, holes 15^a being provided to receive the axial support for said pulley. A rope or 5 cable 16 passes around the sheave 15 and has one end attached to the frame at the point indicated by 17; the other strand of the rope passing over a swiveled sheave 18 supported by the frame and thence to the motor or 10 engine, not shown, whereby the same may be operated as required to raise the boom, and to permit the boom to be lowered when it is desired to make an excavation.

The dipper handle is composed of a beam 15 19 extending between the beams 11 near their outer ends. A bracket 20 is secured to the outer edge of the handle 19 approximately midway between the upper and lower ends of the handle; and is supported 20 by a pivot 21 passing through the beams 11 and through the bracket 20. The bracket 20 may be secured to the dipper handle in different adjusted positions so that the position of the bracket relative to the upper and 25 lower ends of the dipper handle may be varied when it is desired to obtain greater or less length of the handle below the boom. For this purpose spaced holes 20^a are formed through the dipper handle adapted to receive 30 the bolts which support the bracket 20; so that the bracket may be bolted to the dipper handle at any desired altitude.

It will be observed that an important feature of the invention involves this method of 35 mounting the dipper handle by placing the dipper handle operatively between the beams 11 and supporting the dipper handle upon a pivot which is between the outer edge of the dipper handle and the outer ends of the 40 beams forming the boom.

The dipper 22 is open at the top and is supported from the lower end of the handle 19 by a number of straps or arms 23. It will be observed that the dipper is arranged 45 so that when a load is in the dipper the handle 19 will be held by the weight of the load in a vertical position, because the load will be directly below the lower end of the dipper handle. This is because the dipper 50 extends for a distance outwardly beyond the plane of the outer edge of the dipper handle as well as inwardly beyond the inner edge. Thus, when the boom is raised, the dipper will not be dipped or tilted by the weight of 55 the load, as occurs in many excavating machines heretofore used; but the dipper is arranged so that the weight of the load will balance the dipper.

The open side or end of the dipper is 60 toward the mast so that in order to take a load it is necessary to draw the dipper toward the machine, which may be accomplished by a rope or cable 24 connected to the dipper and passing over or against pulleys or sheaves 25 supported by the mast 1

and thence to appropriate operating mechanism.

After the dipper has been loaded the boom is raised by operation of the rope or cable 16; the mast 1 is turned to swing the boom 70 and the dipper laterally by operation of the rope or cable 10; and after the dipper has been swung to the point desired the load is discharged. The load may be discharged from the dipper by swinging the dipper 75 handle 19 to the position shown in Fig. 2. This operation may be effected by a rope or cable 26 having one end connected to the upper end of the dipper handle, the rope or cable passing over a pulley or sheave 27 80 carried by the frame and thence to appropriate operating mechanism. The rope or cable 26 may be operated with a sudden pull or jerk to draw the dipper from under the load, thus discharging the load therefrom. 85 The location of the sheave 27 may be varied to conform to the adjustment of the dipper handle. Also, the cable 26 may be passed under a pulley 26^a and thence over the pulley 27, in instances where such operation and 90 adjustment are desired; or, the cable 24 may be passed over the pulley 26^a. The construction and arrangement of the different parts may be varied in other particulars which do not require specific mention. 95

From the foregoing it will be observed that my invention comprises many important features of construction which not only strengthen the machine, but also simplify and render certain and effective the control 100 and operation of the machine, both in excavating and discharging the material.

I do not restrict myself to unessential features, but what I claim and desire to secure by Letters Patent, is:—

105

1. A machine of the character described, comprising a vertical mast arranged to turn around a vertical axis; a boom composed of two parallel beams having their inner ends on opposite sides of the mast; a pivot on the inner side of the mast supporting said beams; means for raising the boom; a dipper handle located between the outer portions of the boom beams; a pivot supporting the dipper handle and located between the outer 110 edge of the dipper handle and the ends of the boom; and a dipper supported by the lower end of the dipper handle. 115

2. A machine of the character described, comprising a vertical mast arranged to turn around a vertical axis; a boom composed of two parallel beams having their inner ends on opposite sides of the mast; a pivot on the inner side of the mast supporting said beams; means for raising the boom; a dipper handle located between the outer portions of the boom beams; a pivot supporting the dipper handle and located between the outer edge of the dipper handle and the ends of the boom; a dipper supported by the 120 125 130

- lower end of the dipper handle; and means for operating the dipper.
3. A machine of the character described, comprising a vertical mast; means for turning the mast about a vertical axis; a boom pivotally supported on the mast; a dipper handle; a pivot located between the outer edge of the dipper handle and the outer ends of the boom supporting the handle in connection with the boom; a dipper having an open side toward the mast; means for supporting the dipper in connection with the lower end of the handle; and means for drawing the dipper toward the mast in excavating.
4. A machine of the character described, comprising a vertical mast; means for turning the mast about a vertical axis; a boom pivotally supported on the mast; a dipper handle; a pivot located between the outer edge of the dipper handle and the outer ends of the boom supporting the handle in connection with the boom; a dipper having an open side toward the mast; means for supporting the dipper in connection with the lower end of the handle; means for drawing the dipper toward the mast in excavating; means for raising the boom; and means for operating the dipper handle to discharge the load from the dipper.
5. A machine of the character described, comprising a vertical mast; a boom pivotally supported by the mast; a dipper handle; a pivot located between the outer edge of the dipper handle and the outer ends of the boom midway between the upper and lower ends of the dipper handle for supporting the dipper handle in connection with the boom; a dipper supported in connection with the lower end of the handle and having an open side toward the mast; means for drawing the dipper toward the machine in excavating; means for raising the boom; means for turning the mast to swing the boom and the dipper laterally; and a connection from the upper end of the dipper handle for operating the dipper to discharge the load therefrom.
6. A machine of the character described, comprising a vertical mast; ball and socket bearings supporting the mast in a vertical position for rotation about a vertical axis; a boom having its inner end pivotally supported at the inner side of the mast; a dipper handle; a pivot between the outer edge of the handle and the outer end of the boom supporting the handle in connection with the boom; means for drawing the dipper toward the machine to load; means for raising the boom and the dipper after the latter has been loaded; means for swinging the dipper laterally; and means for discharging the load from the dipper.
7. In a machine of the character described, a revoluble mast; a boom pivotally supported by the mast; means for raising the boom; a dipper handle pivotally supported near the outer end of the boom and having one end thereof extending above the boom and the other end thereof extending below the boom; a dipper having side walls and a bottom wall supported below the lower end of the handle in such position that when the dipper is loaded the center of the weight thereof is in axial alinement with the dipper handle; a connection from the dipper for drawing the dipper toward the machine to load; and a connection from the upper end of the dipper handle for jerking the dipper handle to throw the dipper outwardly from the machine and beyond the outer end of the boom to discharge the load from the dipper.
8. A machine of the character described, comprising a frame; a boom pivotally supported in the frame; a dipper handle pivoted to the outer end of the boom and having one end extending above the boom; a dipper, having side walls and a bottom wall, supported below the lower end of the handle in such position that when the dipper is loaded the center of the weight thereof is in axial alinement with the dipper handle; a pulley supported within the frame; a connection from the dipper operating against said pulley for drawing the dipper toward the machine to load; a pulley supported by the boom; a second pulley supported by the frame; a cable passing around said last-named pulleys and operable to raise the boom; a third pulley supported by the frame; and a connection from the upper end of the dipper handle above the boom passing over said third pulley for jerking the dipper handle to throw the dipper outwardly from the machine beyond the outer end of the boom to discharge the load from the dipper.
9. A machine of the character described, comprising a frame, a mast revolvably mounted in the frame, a boom pivotally supported by the mast, a sheave supported by the boom, a rope passing around the sheave and having one end connected to the frame above the boom, a pulley supporting the intermediate portion of the other end of the rope, and a dipper operatively supported by the boom.
10. A machine of the character described, comprising a frame, a mast revolvably mounted in the frame, a boom pivotally supported by the mast, a sheave supported by the boom, a rope passing around the sheave and having one end connected to the frame above the boom, a pulley supporting the intermediate portion of the other end of the rope, a dipper handle supported by the boom, a sheave supported by the frame above the boom, a rope connected to the upper end of the handle above the boom and

passing over said heave, a dipper in connection with the lower end of the handle and having an open side toward the machine, and means for drawing the dipper 5 toward the machine to load.

11. In a machine of the character described, a frame, a journal member secured to the bottom of the frame, another journal member secured to the upper portion of the 10 frame, a mast, a spherical bearing member on each end of the mast journaled in said journal members respectively, means for turning the mast, a boom pivotally supported by the mast, a dipper operatively supported by the boom, and a device for drawing 15 the dipper toward the machine to load.

12. A machine of the character described, comprising a revolute mast; a boom; means for supporting the boom in selected positions on the mast; a dipper handle pivotally supported near the outer end of the boom and having one end thereof extending above the bottom and the other end thereof extending below the boom; a dipper supported by 25 the dipper handle below the boom; means for operating the dipper to load the same; and a connection from the upper end of the dipper handle for operating the dipper to discharge the load.

13. A machine of the character described, comprising a revolute mast, a boom, means for supporting the boom in selected positions on the mast, a dipper handle, means for supporting the dipper handle in different 35 adjustments in connection with the mast, a dipper supported by the handle, and a device for drawing the dipper toward the machine to load.

14. A machine of the character described, comprising a frame, a boom, means for supporting the boom at different altitudes within the frame, a dipper handle operatively supported by the boom, a dipper supported by the handle having an open side toward 45 the frame, means for drawing the dipper toward the frame to load, and means for operating the handle to throw the dipper outwardly from the frame to unload.

15. A machine of the character described, comprising a revolute mast, a frame in which said mast is operatively mounted, a boom, means for supporting the boom in different selected adjustments on the mast, means for raising the boom, a dipper handle 55 supported by the boom and having one end above the boom and the other end below the boom, a rope connected to the upper end of the handle above the boom, a dipper supported by the lower end of the handle in balanced position relative to the handle, and means for drawing the dipper toward the machine to load.

16. A machine of the character described, comprising a frame; a vertical mast mounted in the frame for turning movements; a boom; means whereby the boom may be pivotally supported at selected elevations on the mast; a dipper handle in connection with the boom; a dipper supported by the lower end of the dipper handle; a flexible connection from the dipper for operating the same to load; a pulley on the mast against which said connection passes; a pulley supported by the frame; and a flexible connection from the dipper 75 handle above the boom passing over said last-named pulley for jerking the dipper handle to throw the dipper outwardly from the machine to discharge the load from the dipper.

17. A machine of the character described, comprising a frame; a vertical mast mounted in the frame for turning movements; a boom; means for supporting the boom in selected adjustments in connection with the mast; a dipper handle pivotally supported by the boom, a dipper supported by the lower end of the dipper handle; a pulley supported by the mast; a flexible connection operating against said pulley for 90 operating the dipper to load; and means for raising the boom.

18. A machine of the character described, comprising a frame; a vertical mast mounted in the frame for turning movements; a boom; means for supporting the boom in selected adjustments in connection with the mast; a dipper handle pivotally supported by the boom; a dipper supported by the lower end of the dipper handle; a pulley supported by the mast; a flexible connection operating against said pulley for 100 operating the dipper to load; means for raising the boom; and means for turning the mast to swing the boom laterally.

19. A machine of the character described, comprising a frame; a vertical mast mounted in the frame for turning movements; a boom; means for supporting the boom in selected adjustments in connection 110 with the mast; a dipper handle pivotally supported by the boom; a dipper supported by the lower end of the dipper handle; a pulley supported by the mast; a flexible connection operating against said pulley for 115 operating the dipper to load; means for raising the boom; means for turning the mast to swing the boom laterally; and a flexible connection from the upper end of the dipper handle above the boom for jerking the dipper handle to throw the dipper outwardly from the machine to discharge the load from the dipper.

EPHRAIM J. KEITH.
